UNITED STATES PATENT OFFICE.

NATHAN O. BOND, OF FAIRFAX COURT-HOUSE, VIRGINIA, ASSIGNOR OF THREE-EIGHTHS TO S. J. MEEKS AND A. S. JOHNSON, OF WASHINGTON, DISTRICT OF COLUMBIA.

MATCH-SAFE.

SPECIFICATION forming part of Letters Patent No. 498,377, dated May 30, 1893.

Application filed January 10, 1893. Serial No. 457,928. (No model.)

To all whom it may concern:

Be it known that I, NATHAN O. BOND, a citizen of the United States, residing at Fairfax Court-House, in the county of Fairfax and State of Virginia, have invented certain new and useful Improvements in Match-Safes; and I do declare the following to be a full, clear, and exact description of the invention, such as will enable others skilled in the art to which it appertains to make and use the same, reference being had to the accompanying drawings, and to the letters of reference marked thereon, which form a part of this specification.

The object of this invention is to provide a match safe peculiarly adapted to be suspended from some fixed point, and particularly adapted to be attached to a gas fixture and hang down in easy reach, so that matches can be kept near the burner and thus facilitate lighting the gas.

In constructing my match safe, in addition to providing it with means by which it may be suspended, and a secure receptacle or compartment in which to place the matches, I have aimed to give it such appearance as will make it an ornament. I have also provided a receiver for burned matches.

In order to enable others skilled in the art to which my invention appertains to make and use the same, I will proceed to describe its construction and use, reference being had to the accompanying drawings, in which—

Figure 1 is a perspective view. Fig. 2 is a central vertical section showing the match holding box in its normal position. Fig. 3 is a view showing the match holding box pulled down, the body and burned match receiver being in section; and Fig. 4 is a transverse section taken on line 4—4 of Fig. 2.

Referring to the drawings, A denotes the body preferably of balloon shape, having an opening in the lower end to receive the match holder consisting of a round or other shaped box B, open on one side as at C. This opening extends from near the bottom of the box upward sufficiently to allow a match to be easily removed, and at the same time leaving ledges, D, D', at top and bottom to prevent the matches falling out of the box when it is pulled down out of the body A.

The burned match receiver E is supported by a tube F passing up through the box B as clearly shown by the drawings. The body A and the box B for holding matches as also the burned match receiver E are held together by an elastic cord G, extending up through the tube F and secured to the top of the body A in any suitable manner. The lower end of the cord G being secured against passing through the tube, it will obviously be understood that when the match holder or box B is pulled down and sufficiently far out of the body A admitting of a match being taken, the cord will be stretched so that when the box is released it will be drawn up into the body A and out of sight.

I have shown the burned match holder E in the shape of an open umbrella turned upside-down, but I would have it understood that I do not desire to be limited to the special shape shown as the configuration may be varied according to the desire of the manufacturer. For suspending the device, I have shown a wire H connected with the outside upper end of the body A. This wire may, at its upper end, be formed hook shaped, or be provided with a slip loop. In fact any well known means may be resorted to for securing the match safe securely in position. I would further add that I do not desire to be limited to the balloon shape of the body A as its external form may be varied according to the desire of the manufacturer provided always that it shall be adapted to receive the match box as hereinbefore described in connection with the shape shown by the drawings.

Having thus fully described my invention, what I claim as new, and desire to secure by Letters Patent, is—

1. In a match safe, an inclosing body having a suspending wire secured thereto at its upper closed end, in combination with a match receptacle having flanges for holding the matches, and held in the inclosing body by an elastic cord, the receptacle constructed to be pulled down through an opening in the lower end of said inclosing body against strain of the elastic cord, substantially as described.

2. In a match safe, an inclosing body having a suspending wire secured thereto at its upper end, in combination with a match recep-

tacle having flanges for holding the matches, and held in the inclosing body by an elastic cord, the receptacle constructed to be pulled down through an opening in the lower end of said inclosing body against strain of the elastic cord, and a burned match holder connected with the match receptacle and arranged directly under it, substantially as shown and described.

10 3. The combination of the inclosing body

A, match holding box B, receiver E, tube F, elastic cord G and suspending wire H, all constructed and arranged substantially as shown and described.

In testimony whereof I affix my signature in presence of two witnesses.

NATHAN O. BOND.
